UNITED STATES PATENT OFFICE

GEORGE E. LAND, OF PITTSBURGH, PENNSYLVANIA, ASSIGNOR TO H. E. MARKS CORPORATION, OF PITTSBURGH, PENNSYLVANIA, A CORPORATION OF PENNSYLVANIA

BASE FOR PLASTIC MATERIAL

Application filed March 7, 1929. Serial No. 345,109.

My invention relates to bases for plastic materials and more particularly to unitary bases for plastic materials comprising a fabric, generally metallic, and a backing secured together and adapted for unitary application to supporting structures.

In utilizing bases for plastic material the fabric should be completely imbedded in a covering of plastic material so that when the plastic material is hardened the fabric constitutes an imbedded reinforcing network. The backing serves to support the plastic material before it hardens so that it adheres to the fabric and fills the meshes therein. Where the fabric is so close to the backing that the plastic material does not completely flow around and encase the strands of the fabric, the fabric is liable to be eroded in use with a resultant weakening and/or failure of the hardened plastic body.

In accordance with well-known laws, the value of reinforcing members imbedded in a body of hardened plastic material depends to a considerable extent upon the location of the reinforcement relative to the areas of compression and tension in the hardened material. For the foregoing reasons the fabric and backings of such bases have heretofore been held together by securing devices of such length as to permit the fabric to assume the desired spaced relation to the backing. However, in applying such bases to supporting structures care must be exercised to insure that the fabric is properly spaced from the backing. Workmen in nailing or otherwise securing the bases to the supporting frames are liable to attach the bases to the frames in such manner that the fabrics are very close to, if not in actual engagement with, the backing.

I provide a unitary base for plastic materials in which a fabric and backing are secured together by a plurality of separate spaced securing means passing through the backing. The outer portion of each securing means engages a surface of the backing remote from the fabric and the other end is secured to the fabric. Each securing means is also provided with means engaging an inner surface of the backing for positively

maintaining a definite spaced relation between the backing and the fabric.

The backing comprises a sheet of material which may be a metallic sheet, or a sheet of vegetable matter with or without reinforcing strips. The reinforcing strips, when used, are placed against the skeleton structure to which plastic material is to be applied. The reinforcing strips space the sheet from the supporting structure a distance corresponding to the thickness of the laths ordinarily used in building structures so that the base for plastic material may be applied to standard building frames without requiring any special framing or positioning of the frames to accommodate them to use with such bases.

Certain features of the present application constitute improvements over the subject-matter of my co-pending application Serial No. 193,451, filed May 23, 1927.

The accompanying drawings illustrate certain present preferred embodiments of the invention in which:

Figure 1 is a broken face view of a portion of a base for plastic materials imbedded in a body of material together with supporting members;

Figure 2 is a sectional view thereof taken substantially along the section line II-II of Figure 1;

Figure 3 is a sectional view of modified form of the invention; and

Figures 4, 5, 6 and 7 are similar views of further modifications of the invention.

Referring to Figures 1 and 2, a base 2 for plastic materials comprises a fabric 3 having intersecting strands 4 and 5 defining openings or meshes 6 therebetween, a backing 7 comprises a sheet 8 and stiffening members 9, and securing means 10 extending through the backing and engaging the fabric 3. A positive spaced relation between the backing 7 and the fabric 3 is secured by providing positive spacing means 11 therebetween.

One form of securing means 10 is that of a wire or nail having a bent portion or head 12 engaging a surface of the backing 7 remote from the fabric 3, such as a stiffening strip 9 into which it is slightly imbedded. A sub-

stantially straight portion 13 or shank extends through an opening 14 in the backing. The opening 14 preferably fits the wire or nail tight enough to prevent the passage of 5 plastic material through the opening when the securing means is in place. Each wire or nail is provided with a loop 15 passing around one of the strands of the fabric, or to which it may be welded, if desired. The 10 outer end 16 of the wire or nail is doubled back into engagement with the portion 13 with its end in engagement with an inner surface of the sheet 8. Accordingly, relative movement between the fabric 3 and the backing 7 is prevented.

The provision of a definite spaced relationship between the fabric and backing insures sufficient space between them so that plastic material will completely encase the fabric 20 and also that the fabric shall be maintained in substantially the plane of greatest usefulness in the hardened plastic material. In general, the fabric should be imbedded in the plastic material at a distance from the bottom there- 25 of equal to approximately one-third of the depth of the material.

The stiffening strips 9, sheet 8, fabric 3 and securing means 10 are assembled in a shop and are transported as a unit to the 30 walls or supporting structure to which the base is to be applied. By providing a unitary base for ready application to such supporting structures, the trouble incident to separately applying the backing and fabric to 35 the structure and securing them in place in situ is eliminated.

Rigidity in handling the base is obtained by the presence of the stiffening strips 9. The strips are preferably given a thickness 40 equal to the thickness of laths ordinarily used in building constructions. By providing such stiffening strips the sheets 8 and fabric 3 are spaced the same distance from the supporting frames as though a layer of 45 lath were interposed. The use of frames of special dimensions or the use of specially sized timbers and supports are not necessary for accommodating the structures to the use of bases for plastic materials since the stiffening strip 9 occupies the space normally allotted to laths.

In applying such bases to supporting structures, fastening means are secured to the stiffening strips and the supporting structures. Where the supporting structures are in the form of timbers 17, fastening means, such as nails 18, are driven through the sheets 8, the stiffening members 9 and into the timbers 17.

60 Since the nails 18 only pass through the sheet 8 and the stiffening strips 9, slight relative movement between timbers 17 and the body 19 of hardened plastic material does not cause cracking of the plastic material.

65 Where the securing means, such as nails, ex-

tend into the body of hardened plastic material, forces applied to them are transmitted to the hardened plastic material with deleterious effect.

In my construction a slight amount of relative movement may take place between the timbers 17, the nails 18 and the hardened body 19 without stressing the latter since the stiffening strips 9 and sheet 8 may be slightly deformed without severely straining the body 19.

The fabric 3 may be of any form of wire netting or metallic lath having open meshes between intersecting metallic strands and it may be formed by perforating, weaving or welding as desired. For the purpose of developing the full reinforcing value of the steel fabric in accordance with the established engineering practice of overlapping adjacent edges of the fabric, it is contemplated that the area of the steel fabric may be larger than the area of the backing so that the fabric may extend past or overhang the backing along any one or all of the sides or edges of the backing.

The sheets 8 may be metal, paper, cloth or other material suitable for supporting the plastic material before the latter adheres. Such bases for plastic materials are used for retaining and/or reinforcing plastic materials, and for providing sound-deadening, fireproofing, insulating, and water proofing barriers in buildings. The base is adapted for use with a wide variety of plastic materials, such as plaster, stucco, concrete, gypsum and like materials. Such materials may be applied to the base by pouring, spreading, spraying or troweling for forming interior or exterior walls, ceilings, floors and the like.

Referring to Figure 3, securing means 20 have their ends 21 completely imbedded in the stiffening strips 9 by driving the nails downwardly through the sheet 8 and stiffening strip 9 against a deflecting member such as an anvil (not shown). The other end 22 of the nail is bent around the fabric 3 to space it from the sheet 8.

Referring to Figure 4, the fabric 3 may be attached to the sheet 8 and stiffening strip 9 by staples 24 which straddle a strand of the fabric. The ends of the staples 24 penetrate the sheet 8 and stiffening strips 9. The outer ends 25 of the staples are clenched to the strips 9. By drawing the legs 26 of the staples together intermediate the fabric 3 and the sheet 8, the latter are held in definite spaced relation.

In Figure 5 I have illustrated a form of my invention in which only a fabric 3 and sheet 8 are utilized, stiffening strips being omitted. In this form of the invention, which is otherwise the same as that shown in Figure 2, the securing nails are provided with the bent

portions or heads 12 directly engaging the sheet 8, spacing means 11' and loops 15'.

Referring to Figure 6, I have illustrated a form of my invention in which a fabric 3 is connected to a layer 27 of wallboard by nails 28. Bent portions or heads 29 of the nails are clinched to the outer surface of the wall board. Loop portions 30 engage strands of the fabric 3 and the ends 31 are curved to bear against the inner surface of the wallboard 27, thereby spacing the fabric and wallboard.

Referring to Figure 7, the bent portions or the heads 12' of the fasteners shown in Figure 5 of the invention and the sheet 8' may be covered by a sheet 32 of covering material, an example of which is tar paper. This construction gives a double backing to the base.

While I have shown and described specific forms of securing means in connection with the several embodiments of the invention, it is to be understood that other forms of securing means may be substituted for the specific forms shown and that such substitutions are contemplated within the spirit of the invention.

While I have shown and described certain present preferred embodiments of the invention, it is to be understood that it may be otherwise embodied without departing from the spirit of the invention or the scope of the appended claims.

I claim:

1. A unitary base for plastic materials comprising a fabric, a backing, and wire staples for securing the fabric and backing together, said securing staples having a portion for maintaining a spaced relation between all parts of the fabric and the backing.

2. A unitary base for plastic materials comprising a fabric, a backing and wire staples for securing the fabric and backing, said securing staples comprising integral means for maintaining a spaced relation between all parts of the fabric and backing.

3. A unitary base for plastic materials comprising a fabric, a backing, and wire staples extending through the backing and engaging the fabric for securing the fabric and backing together, said securing staples having a portion for maintaining a spaced relation between all parts of the fabric and backing.

4. A unitary base for plastic materials comprising a fabric, a backing, means extending through a tightly fitting hole in the backing and engaging the fabric for securing the fabric and backing together, and means interposed between the fabric and backing for maintaining a spaced relation between them.

5. A unitary base for plastic materials comprising a fabric, a backing, and securing means extending through a plurality of spaced openings in the backing for holding the fabric and backing together, a portion

of each securing means being effective upon a surface of the backing remote from the fabric and another portion being effective upon a closer surface of the backing whereby the backing and fabric are held in definite spaced relation.

6. A unitary base for plastic materials comprising a fabric, a backing comprising stiffening means, and separate means extending through a plurality of spaced openings in the backing for securing the fabric to the stiffening means and for maintaining a spaced relationship between the backing and the fabric.

7. A unitary base for plastic materials comprising a fabric, a backing comprising stiffening means, securing means engaging the fabric and the stiffening means for securing the backing and fabric together and in spaced relationship to one another, whereby means for securing the base to a supporting structure and cooperating with the stiffening means are free to move relative to the fabric without materially stressing a body of hardened plastic material embedding the fabric.

8. A base for plastic materials comprising a fabric, a backing and means for securing the fabric to and in entire spaced relationship with the backing, said backing comprising a substantially continuous sheet of paper for holding plaster and stiffening strips of wood secured thereto by said fabric-backing securing means.

9. A base for plastic materials comprising a fabric, a backing and means for securing the fabric to and in entire spaced relationship with the backing, said packing comprising a substantially continuous sheet of paper for holding plaster and stiffening strips of wood having substantially the thickness of commercial lath secured thereto by said fabric-backing securing means and by which the base may be readily attached to a supporting structure.

10. A backing for a base for plastic materials comprising a continuous sheet of material and stiffening means secured exclusively to that side of the sheet not covered by the plastic material for spacing the backing from supporting means.

11. A unitary base for plastic materials comprising spaced transverse stiffening members, a backing, wire staples for securing the spaced members and the backing together, said staples having means for maintaining a spaced relation between all parts of the spaced members and the backing.

12. A unitary base for plastic materials comprising a plurality of spaced longitudinal stiffening and reinforcing members, a backing, and staples for securing the longitudinal members and backing together, said staples having integral means associated therewith for maintaining a uniform spaced relation-

ship between all parts of the longitudinal members and the backing.

13. A unitary base for plastic materials comprising a plurality of spaced transverse and longitudinal stiffening and reinforcing members, a backing, and staples having integral means for securing the backing and the longitudinal and transverse members together and in entire spaced relationship with respect to each other.

In testimony whereof I have hereunto set my hand.

GEORGE E. LAND.
